US0D1109175S

(12) **United States Design Patent** (10) Patent No.: **US D1,109,175 S**
 Sue et al. (45) Date of Patent: ** Jan. 13, 2026

(54) **DISPLAY SCREEN WITH GRAPHICAL USER INTERFACE**

(71) Applicant: **Jona, Inc.**, Stamford, CT (US)

(72) Inventors: **Jillian Joo-Ae Sue**, New York, NY (US); **Audrieanna Marlieza Walker-Muller**, Los Angeles, CA (US); **Maclay Adison Ramsey**, Nashville, TN (US)

(73) Assignee: **Jona, Inc.**, Stamford, CT (US)

(**) Term: **15 Years**

(21) Appl. No.: **29/959,195**

(22) Filed: **Aug. 23, 2024**

(51) LOC (15) Cl. **14-04**

(52) U.S. Cl.

USPC **D14/486**

(57) **CLAIM**

The ornamental design for a display screen with graphical user interface, as shown and described.

DESCRIPTION

The FIGURE is a front view of a display screen with graphical user interface showing our new design.

The broken line perimeter showing the display screen forms no part of the claimed design. The remaining broken lines showing text and elements of the graphical user interface form no part of the claimed design.

1 Claim, 1 Drawing Sheet
